POTENTIOMETERS

Richard E. Caddock, Riverside, Calif., and Marlan E. Bourns, 2530 Piedmont Drive, Riverside, Calif.; said Caddock assignor to Bourns, Inc., a corporation of California

Filed Nov. 14, 1960, Ser. No. 69,060
20 Claims. (Cl. 338—180)

This invention relates to new and improved variable resistors such as potentiometers; and is a continuation-in-part of application Ser. No. 743,308 filed by the inventors hereof on June 20, 1958.

At the present time potentiometers of one type are manufactured so as to include a housing within which here is mounted a resistance element and a threaded shaft extending parallel to the resistance element. In instruments of that type a contact device is moved by the shaft as the shaft is turned, the contact device moving along the length of the resistance element and establishing an electrical connection between the element and a part of the potentiometer serving as an electrical return. In some potentiometers of that type the shaft itself is employed as the electrical return; in others, a separate conductor is employed as an electrical return or shorting trip.

Some potentiometers of the type briefly described in the preceding paragraph are manufactured so as to be of comparatively small size. As a result of this miniaturization a number of problems are encountered in manufacturing at a reasonable cost instruments which are capable of withstanding normal abuse incident to handling, installation and use. Typical of the types of abuse that may occur is that occurring when an operator turns the threaded shaft employed in this type of potentiometer too far in either direction and thereby causes the contact device to travel too far and press against either of the ends of the unit. Such operation or excessive shaft rotation will tend to strip the threads connecting the shaft with the contact device. When this occurs the potentiometer is damaged to such an extent that its utility is impaired if not completely destroyed.

A broad object of the present invention is to provide a new type of contact device for use in potentiometers. More specifically it is a broad object of this invention to provide a new type of contact device which overcomes disadvantages and limitations of prior types of variable resistor contact devices. In accordance with the broad teachings of this invention, these general objects are achieved through the use of a contact device or means which has a groove that is disposed against one side of a threaded shaft, and a spring-like element extending over the shaft so as to hold the device and shaft together with the shaft positioned in the groove. The spring-like element is formed so as to resiliently engage the thread of the shaft. The construction and arrangement of the spring-like element is such that it is capable of moving or "snapping over" the thread on the shaft when the shaft has been turned to an extent such as to force the contact device against some obstruction such as, for example, an end of a housing in which the parts are disposed.

Another object of the present invention is to provide a new type of potentiometer construction in which a contact device is formed entirely of metal and in which the contact device electrically interconnects the threaded metal shaft of the potentiometer with the resistance element employed.

A further object is to provide in this type of instrument a spring-like shaft-retaining clip which serves as a

2

terminal for the shaft used as an electrical return. Another object of the present invention is to provide a new type of terminal construction for use with resistance elements such as may be employed in potentiometers.

5 Another object of the present invention is to provide a new type of contact device as described in the preceding paragraphs in which contact member a groove is formed in a non-conductive body member and in which device separate spring means are employed so as to resiliently engage a threaded shaft as herein indicated. With this type of contact device construction the complete device includes contact means which are attached to a body member, and which contact means extend from the body member so as to engage a resistance element and a return conductor. Another object of the present invention is to provide in potentiometers a new and improved construction for securing a resistance element in place.

Additional objects and advantages of the invention will become fully apparent to those skilled in the art to 20 which this invention pertains from a detailed consideration of the remainder of this specification, including the appended claims and the accompanying drawing in which:

FIG. 1 is a perspective view of a potentiometer according to this invention;

FIG. 2 is a cross-sectional view taken as indicated by line 2—2 of FIG. 1;

FIG. 3 is a cross-sectional view taken as indicated by line 3—3 of FIG. 2;

FIG. 4 is a partial cross-sectional view taken as indicated by line 4—4 of FIG. 2;

FIG. 5 is a perspective view illustrating a contact device employed in the potentiometer illustrated in the previously described figures;

FIG. 6 is a partial cross-sectional view taken on a plane indicated by line 6—6 of FIG. 2;

FIG. 7 is a view similar to FIG. 2, depicting in partial section a modified form of potentiometer according to this invention;

FIG. 8 is a partial cross-sectional view taken as indicated by line 8—8 of FIG. 7; and

FIGS. 9 and 10 are perspective views of parts employed in the potentiometer illustrated in partial section in FIG. 7.

45 In all figures of the drawing like numerals are used to designate like parts wherever convenient for purposes of illustration and explanation. It is to be understood that the accompanying drawing is primarily intended to designate certain presently preferred embodiments or forms 50 of this invention. Those skilled in the art to which the present invention pertains will realize that a number of differently-appearing electrical instruments may be manufactured so as to utilize one or more features of the complete inventive concept set forth in this specification.

55 In order to explain the present invention more fully reference is made to the accompanying drawing. In FIGS. 1, 2 and 3 of the drawing, there is shown a complete potentiometer according to the present invention, which

60 potentiometer includes two substantially symmetrical housing sections 12 formed of a phenolic resin or other similar non-conductive composition. These two sections are adapted to be secured together as shown and are so shaped or formed as to define within the potentiometer

65 10 an elongate cavity 14 having ends 16 and 18 and to define various other passages and cavities as hereinafter described. The two sections 12 are assembled and secured together by means hereinafter described, to form a body or housing. Therein, a complete resistance element 20 having a nonconductive mandrel 22 is located with its ends held in sockets 24 formed by complemen-

70

tary depressions produced in the sections 12, the sockets being situated in the ends 16 and 18 of the cavity 14, as indicated in FIG. 2. Resistance wire 26 is wound over the mandrel 22, and at the ends of the element are terminals 28. Each of the terminals 28 has a ring-shaped end portion 30 (FIG. 4), which encircles the wire windings at the end of the element to make electrical contact therewith. Notches 34 in the terminals 28 fit over projections 32 in small passages leading from the cavity 14 to the outside of the potentiometer 10, so as to lock these terminals in place.

A metal shaft, or leadscrew 38, formed as indicated, is carried in openings 40 and 42 formed in the housing at respective ends 16 and 18 of the cavity 14, the leadscrew extending in cavity 14 parallel to the resistance element 20. Shoulder or abutment means, here shown in the form of a radial flange 44, is formed on the shaft near the right-hand end thereof, and this flange 44 is located within a smaller cavity 46 defined by opposed depressions produced in respective ones of the housing sections 12. The flange 44 bears against a complementary abutment 47 provided in one or both of sections 12 which abutment 47 faces toward the right-hand end of the body, as seen in FIG. 2 so as to position the leadscrew 38 within the body and prevent endwise movement of the leadscrew toward the opposite end of the body. The right-hand end of the leadscrew or shaft 38 is provided with a flat-sided portion 48 which is slidably received within a correspondingly shaped cavity 58 in a non-conductive head 52.

The head 52 may be formed of "plastic" such as a hardened resin or the like, and is movably held within a complementary cylindrical cavity 50 in the end of the instrument body. A radial flange 54 on the head 52 is seated within an annular groove 56 formed in the wall of the cavity 50, and this serves to prevent endwise movement of the head 52 while permitting the latter to turn freely in the instrument body. Thus, when the head 52 is turned as by the use of a screwdriver (not shown) engaging a slot 60 in this head, the entire shaft 38 is turned.

As the shaft 38 is turned a movable contact device, 62, located within the cavity 14 is moved between the ends 16 and 18 of that cavity through engagement of a spring-like U-shaped wire 64 with the thread 66 of the leadscrew or shaft 38 within the cavity 14. As indicated in the drawing, the contact device 62 includes a body member 68 formed out of metal so as to have a smooth groove 70 (FIG. 5) of substantially uniform cross-section, fitting against the threaded portion of the leadscrew. The ends of the resilient wire 64 are suitably attached as by welding or equivalent techniques to body member 68 in such a manner that the base 72 of the wire 64 fits and rides between next adjacent teeth of the thread 66 so as to resiliently engage the leadscrew and so hold the shaft 38 within the groove 70 and move the contact device 62 longitudinally of the leadscrew as the latter is rotated.

A small contact means 74 or brush of a resilient character is provided, preferably formed integrally with the body member 68 as shown, and is constructed and arranged to resiliently engage the resistance element 20. The sides of the body member 68 are constructed and arranged as shown to fit within grooves 76 (FIG. 6) formed in the sections 12—12 at the sides of cavity 14, in order to prevent rotation of the contact device 62 as the shaft 38 is turned. As the shaft is turned, the contact device 62 electrically connects the shaft 38 with the resistance element 20.

In order to complete the electrical circuit in the described FIG. 2 embodiment of potentiometer 10 a spring means or clip 78 having a bifurcated end 80 is disposed with its forked end within the cavity 46 and so arranged that the end 80 resiliently engages and presses against the flange 44 as shown, in order to hold shaft 38 against longitudinal movement of flange 44 away from abutment 47 and in order to establish electrical contact with the shaft.

Preferably the end 80 is formed so that the pressure against the flange 44 is applied equally on opposite sides of the shaft 38.

The clip 78 may conveniently serve as a terminal, and for that purpose is illustrated as including an end 82 disposed as shown and extending through a passage 84 to the outside of the potentiometer 10. This end 82 is provided with notches 86 (FIG. 3) which engage projection 88 formed on the mating surfaces of the housing sections 12, in order to securely latch the clip in place.

Those skilled in the art to which this invention pertains will realize that with the type of construction of the movable device 62 illustrated in FIGS. 2, 5 and 6, danger of damage to the leadscrew and contact device from excessive leadscrew rotation is substantially eliminated. As the shaft 38 is turned to excess, forcing contact device 62 against either of the ends 16 or 18 of the cavity, the wire 64 will spring up and snap over a portion of the tooth or thread 66 until such time as the direction of rotation of shaft 38 is terminated or reversed. Reversal of rotation will in that event cause reversal of movement of device 62. The construction of resilient clip 78 and the manner in which that member is used provides for effectively locking the shaft 38 in place and preventing backlash.

In FIG. 7 of the drawing there is illustrated a modified embodiment of potentiometer 90 according to the present invention. The modified form of potentiometer includes a body member having a non-conductive base 92 and a pair of upstanding ends 94 and 96. The potentiometer body portion including base 92 and ends 94 and 96 may be conveniently formed from a nonconductive material such as a thermosetting phenolic resin, and is preferably made of opposed complementary sections in accordance with the construction shown in FIG. 1, and so as to provide a cavity 100 adapted to be closed by a cover 98. Cover 98 may conveniently be of metal and formed as an inverted trough-like stamping of square U-shaped cross section, with pairs of aligned apertures in the side flanges for accommodation of respective tubular rivets 102, 102 all in a manner and form now well known in the art. Rivets 102 serve also to secure the complementary sections of the body portion together. Base 92 is formed to provide a set of grooves 104 and 106 located at the bottom of cavity 100. The groove 104 is formed and arranged to contain a U-shaped metal shorting strip 108 (FIG. 8), formed in accordance with known technique or as illustrated in Patent No. 2,886,681. The other groove, 106, is adapted to contain a conventional wire wound resistance element 110.

At one side of each of the ends of the resistance element 110 there is located an end 112 of one or the other of a pair of metal terminals such as terminal 114 shown in FIG. 8. Each of the terminals extends through the base 92 by way of a respective groove 106 and passage 116, as indicated in the latter figure. The resistance element 110 is held in electrical communication with protuberances 118, one of which is formed on each of the ends 112 of terminals 114, by means of tapered wedges 120—120. The construction of one of these wedges is best illustrated in FIG. 10 of the drawing. It is then shown that each of the wedges 120 has a curved top 122 and a flat bottom 124 and an intermediate curved, tapered wall portion 126. The wedges 120 are so constructed as to be used that the side edges 128 thereof engage a side of the groove 106.

The wedges 120 are so formed that after the terminals 114 and the resistance element 110 have been located within the groove 106, the wedges can be driven into the positional disposition indicated, to firmly force the ends of resistance element 110 against respective ones of terminals 114 and thus establish reliable electrical connection between the terminals 114 and the ends of the resistive means comprised in resistance element 110. The construction of the wedges 120 for the purpose indicated is extremely advantageous inasmuch as these wedges pre-

ent breaking or otherwise disrupting the resistance winding 130 on the resistance element 110. With prior constructions there has been a problem in satisfactorily establishing reliable electrical termination of a resistance element in this type of construction. Prior clips, etc., have frequently been the source of a certain amount of breakage of resistance windings.

The ends 94 and 96 of the potentiometer body portion movably support a metal shaft or leadscrew 132 which may, as shown, extend to the exterior of the potentiometer. The shaft is formed and supported in a manner and by means now well known in the art, and may be retained in position by conventional means such as a transverse pin 150 that engages in a peripheral groove formed in the screw, or as indicated, for example, in Patent No. 2,823,288. When shaft 132 is turned as by the use of a screwdriver engaging a head 134 provided therefor, a small, movable device 136 is moved longitudinally in a selected direction along leadscrew 132, between the inner faces of ends 94 and 96. As indicated in FIG. 9 of the drawing this movable device includes a non-conductive member 138 so formed as to have a smooth groove 140 of uniform cross-sectional configuration located therein. Groove 140 is preferably of cross-section complementary to the outer periphery of thread 44. The sides of member 138 are constructed and arranged to slide in contact with respective sidewalls of cavity 109, to obviate undesirable rotation of member 138 when shaft 132 is moved. A resilient U-shaped wire 142 similar to the wire 64 previously described is attached to body member 138 so as to engage the thread 144 of shaft 32. A contact means 146 is secured to member 138 and includes one or more brush means 148 constructed and arranged to resiliently engage and electrically interconnect the resistance element 110 and the strip 108. Preferably there are at least two brushes comprised in brush means 148, each of which brushes makes contact with a respective one of the resistance element 110 and the strip 08. The resilient wire 142 and the contact means 146 are attached to the body 138 by any of suitable known techniques, and are so relatively constructed and arranged that the wire 142 is insulated from the contact means 146.

While in the potentiometer illustrated in FIG. 7 a set of rivets 102, 102 may be employed to secure the housing sections together, other means may be employed. For example, a cementitious material may be employed; and in the embodiment illustrated in FIG. 1 an adhesive, or vets or clip means (not shown) may be employed to secure the sections 12-12 together into a unitary structure.

Those skilled in the art to which this invention pertains will realize that both of potentiometers 10 and 90 operate in such a manner that it is virtually impossible to damage these instruments by turning the shafts employed in them so as to wedge or otherwise jam the movable contact device (62 or 136) employed in these instruments against either of the ends of the housing in which the contact device operates. Those skilled in the art will further realize that any of the individual features of these potentiometers shown can be used in a wide variety of differently appearing electrical instruments. For these reasons the present invention is to be considered as being limited only by the appended claims.

We claim:

1. A screwshaft-operated potentiometer comprising: first means, comprising housing means, forming a housing for containing operative elements of the potentiometer; second means, comprising a screw-threaded shaft, supported by said first means and having a threaded portion of the shaft exposed in said housing; third means, comprising a resistance element disposed in said housing with a portion presenting an exposed contact-face generally parallel to said screwshaft; and fourth means, comprising a contact device comprising

a movable member formed with an elongate open-ended trough-like groove therein of depth no greater than the maximum radius of the thread of said shaft and disposed with a threaded portion of said screw-shaft seated in said groove, said contact device comprising spring-wire means having first and second ends secured to said member and a portion bridging said groove and said screwshaft whereby to secure said member to said shaft and to yieldingly traverse said member along the screwshaft incident to rotation of the screwshaft, and said contact device comprising a contact supported by said movable member and disposed to brush on said resistance element, said first, second and third means also comprising means providing a plurality of potentiometer terminal means and means for completing a series electric circuit including a first one of said terminal means and a portion of said resistance element and said contact and a second one of said terminal means.

2. A potentiometer as defined in claim 1, wherein said contact device includes in said spring-wire means a U-shaped resilient metal wire, the ends of said wire being attached to said body member adjacent one end of the latter, the base of said U-shaped wire fitting within the thread on said shaft adjacent the other end of the member so as to resiliently engage said shaft on a side thereof opposite the said groove.

3. A potentiometer as defined in claim 1, wherein said body member is formed of metal.

4. A potentiometer as defined in claim 1, wherein said movable member is formed of a non-conductive material, and wherein said contact device and said spring-wire means are insulated from one another.

5. A potentiometer which includes: a non-conductive housing having a cavity formed therein; means defining parallel first and second grooves at the bottom of said cavity; an electrical return positioned within the first one of said grooves so as to extend into said cavity; a wire-wound resistance element reposing in the second of said grooves so as to extend into said cavity; metal terminal members each disposed against a respective end of said resistance element at one side of said second groove, said metal terminal members being in electrical contact with said resistance element; tapered wedges each having a substantially flat bottom, a curved top and a curved tapered wall having side edges and connecting said top and said bottom, each wedge being positioned in said second groove with the top thereof located adjacent to the top of said second groove, said wedges resiliently holding said resistance element against said terminal members, the side edges of said wedges engaging a side of said second groove; a threaded shaft positioned so as to extend through said cavity within said housing parallel to said resistance element; a non-conductive body member having

55 a smooth groove of substantially uniform cross-sectional configuration formed therein, constructed and positioned so that said smooth groove fits in complementary disposition against said shaft; a U-shaped metal wire spring attached to said body member and so disposed that each of the ends of said U-shaped metal wire is attached to said body member, and so disposed that said U-shaped metal wire extends across said shaft at the side thereof opposite said body member and resiliently engages the thread on said shaft in order to hold said body and shaft together with said shaft in said smooth groove; and contact means attached to said body member, said contact means including brush means constructed and arranged to engage said resistance element and said electrical return, said contact means being insulated from said U-shaped metal wire spring.

6. A potentiometer as recited in claim 1 wherein there is included an improved means for making contact with the ends of said resistance element, comprising a conductive terminal at one end of said resistance element in contact therewith and extending external to said cavity,

and a tapered wedge member driven into said housing adjacent to said one end of said resistance element and on the side opposite to that contacted by said conductive terminal and pressing said resistance element against said conductive terminal to insure better electrical contact between said resistance element and said conductive terminal, said tapered wedge member having a curved top end, a flat bottom end, and a curved tapered wall connecting said top and bottom.

7. In a potentiometer of the type having a housing wherein a threaded shaft is rotatably supported spaced from an elongate resistance means, and a contact device is operatively engaged with said threaded shaft and makes wiping contact with said resistance means incident to movement along the resistance means, an improved contact device comprising: a block of insulating material having a groove formed therein of depth no greater than the maximum radius of the thread of said shaft, for complementary sliding engagement with said threaded shaft, a U-shaped resilient metal wire extending generally longitudinally of said threaded shaft, said resilient wire having ends each attached to said block of insulating material adjacent a respective one of opposite sides of said groove and having its base bridging said groove and extending over said threaded shaft to fit and engage the thread thereof and effective to resiliently hold said block of insulating material to said threaded shaft, and means, including a metal sliding contact carried by said block and constructed and arranged to extend toward said elongate resistance means and to make wiping contact therewith incident to movement of said block along said shaft.

8. A potentiometer having a housing defining a cavity containing a threaded shaft rotatably supported by said housing, an elongate resistance means spaced from said threaded shaft, and a contact device having a conductive body member having a portion of U-shape, the body member being constructed and arranged for slidably engaging said threaded shaft, said contact device having two flanges, each extending away from said portion of U-shape at a respective one of the ends thereof, said housing having opposite walls adjacent said threaded shaft, parallel grooves each in a respective one of said opposite walls, each of said flanges respectively extending into a respective one of said grooves for providing guidance for said contact device as it is moved along said threaded shaft, a contact formed as part of said body member at said portion of U-shape and extending therefrom for engaging the elongate resistance means, and a resilient U-shaped spring extending generally parallel to a plane defined by the said flanges, said resilient U-shaped spring having each of its ends attached to a respective one of said flanges of said contact device and having its base bridging said portion of U-shape and extending over said threaded shaft to fit between teeth of the thread thereof and to resiliently hold said contact device to said threaded shaft.

9. A contact device for use in a variable resistor which resistor comprises an elongate resistance element and a screwshaft, the contact device being constructed and arranged for actuation by the leadscrew to make wiping electrical contact along said resistance element, said contact device comprising:

first means, comprising a body member formed with opposite side portions and an intermediate portion all of which portions are shaped to define a longitudinally-extending concave relatively smooth open groove of dimensions and configuration for complementary reception of a portion of a leadscrew and said groove being of depth no greater than the maximum radius of the thread of said screwshaft;

second means, comprising electrical contact means, supported by said body member and constructed and arranged for cooperation with an elongate resistance element to thereby make electrical contact therewith and to resiliently press said body member against a leadscrew;

and third means, comprising a single generally U shaped resilient wire member having two end portions and a base portion interconnecting the end portions, said end portions being each secured to said body member on respectively opposite sides of said groove and disposed with said base portion bridging said groove and constructed and arranged for engagement with a leadscrew between next-adjacent teeth of the thread thereof for imparting motion along the leadscrew incident to relative rotation therebetween and for holding said body member in close cooperative engagement with such a leadscrew.

10. A contact device according to claim 9, said body member consisting essentially of a deformed sheet-metal plate having opposed flanges, and said contact means comprising essentially a protruding resilient contact finger depending from and integral with the plate, and said resilient wire member having the ends thereof extending through respective apertures formed in said flanges and attached to said body member by fusion therewith.

11. A contact device according to claim 9, said body member comprising essentially a block-like body of electrically insulative material, and said resilient wire member having at least one end thereof embedded in the block-like body to securely attach the wire member to the block member.

12. In a variable resistor, the combination comprising first means, including an elongate resistance element including a resistive means; second means, including means forming a cavity in which the said elongate resistance element reposes; third means, comprising a terminal device, said terminal device being disposed at least in part in said cavity in contact with a portion of said resistive means; and fourth means, comprising a resilient wedge constructed and arranged at least in part in said cavity in contact with said resistance element and resiliently forcing said terminal device and said resistive means into firm electrical contact each with the other thereof.

13. In a variable resistor, the combination defined in claim 12, the said resistive means comprising a resistive wire.

14. For a variable resistor having a body, a resistive element in said body, and a rotatable screwshaft disposed parallel to the resistance element, the improvement comprising:

a contact device constructed and arranged to be supported upon and by the screwshaft for movement therealong incident to rotation of the screwshaft, said device comprising a body having a longitudinally-extending portion formed to accommodate an arcuate portion of the lower half of the periphery of a length of the screwshaft, and said device comprising a spring wire having first and second ends secured to said body and having intermediate said ends respective portions extending generally along said screwshaft and a middle portion extending transversely of said body and bridging said longitudinally-extending portions and arranged to engage in the groove of the thread of the screwshaft and thereby hold the said body to the screwshaft, whereby said body when unrestricted may be traversed along the screwshaft by rotation of the screwshaft and whereby incident to arrestment of the body from longitudinal traverse along the screwshaft the middle portion of said spring wire yields to continue rotation of the screwshaft without damage to the resistor.

15. A contact device for a screwshaft-operated variable resistor having a screwshaft and an elongate resistance element arranged parallel to the screwshaft, said device comprising:

a body member having upper and lower faces and constructed and arranged with an elongate shallow ope

ended groove longitudinally along the upper face thereof for reception therein of a portion of the lower periphery of a length of screwshaft; spring wire means, having first and second ends firmly secured to said body member, and having an intermediate portion bridging said groove and arranged for thread-engagement with the upper surfaces of the screwshaft for securing the body member to the screwshaft and for sliding the body member along the screwshaft incident to rotation of the screwshaft; and a contact carried by said body member and extending downwardly therefrom and arranged to contact and brush on the resistance element.

16. A potentiometer comprising, in combination with an elongate housing comprising a body and which housing forms an enclosure bounded by interior walls and in which housing are enclosed an elongate resistance element and an elongate conductive strip, and an elongate leadscrew supported by the housing and having an end accessible from the exterior of the housing for imparting rotation to the leadscrew, and the leadscrew having a screw-threaded portion exposed within the interior of the housing:

a movable device including a non-conductive member having opposed portions disposed at opposite sides of the leadscrew and having at least one surface arranged to bear against one of said interior walls to prevent rotation of the device with the leadscrew incident to rotation of the leadscrew, said device comprising a resilient bent wire member secured to said non-conductive member and said wire having a single resilient portion extending transversely across the leadscrew and engaged in the groove of the thread of the leadscrew, and said movable device including contact means carried by said non-conductive member and comprising at least two resilient brush means each engaging a respective one of said conductive strip and said resistance element to electrically interconnect the conductive strip to a selected portion of the resistance element; and

terminal means connected to respective ones of said conductive strip and end portions of said resistance element;

whereby, incident to rotation of the leadscrew the said device is moved therealong to electrically connect said conductor strip with various portions of said resistance element until movement of said device is arrested and whereby when movement of said device is arrested continued rotation of said leadscrew induces slippage of said resilient portion of said wire over the rib of the thread to avoid damage to the potentiometer.

17. A potentiometer comprising:

first means, including means forming an elongate housing having at least one interior wall, said housing providing interior space for enclosing resistance element and conductive strip means;

second means, comprising an elongate resistance element disposed longitudinally of said housing and supported thereby and therein, said resistance element having a longitudinally-extending exposed surface within said housing, and said second means including terminal means including terminals connected to respective end portions of said resistance element;

third means, comprising an elongate conductive strip supported by said housing and disposed in said housing adjacent to said resistance element, and said third means comprising a terminal connected to said conductive strip;

fourth means, including an elongate leadscrew means supported by said housing and disposed substantially parallel to the exposed surface of said resistance element, said leadscrew means comprising a threaded portion having a helical rib the convolutions of which are separated by an intervening helical groove and

said leadscrew means having an end portion accessible from outside said housing to permit rotation of at least the said threaded portion; and

fifth means, comprising a movable device disposed in said housing and including a contact-carrying member having at least one portion disposed along said leadscrew and having at least one portion guided by contact with said interior wall to obviate rotation of member with the leadscrew incident to rotation of the latter, said movable device further including a resilient wire supported by said contact-carrying member and carried thereby, said resilient wire having a resilient portion free to move relative to said member and said resilient portion including a portion of said wire extending transversely across and engaging said leadscrew and normally disposed in the said groove of the thread of the leadscrew between adjacent convolutions of the rib thereof, and said resilient portion being adapted to flex and permit the portion thereof engaging the leadscrew to ride over the said rib, and said fifth means comprising a contact carried by said contact-carrying member and insulated from said leadscrew, said contact comprising brush means resiliently engaging and electrically interconnecting said conductive strip and said exposed portion of said resistance element;

whereby incident to rotation of said leadscrew said movable device is moved along said leadscrew until movement of the device is arrested and whereby said conductive strip is electrically connected to various longitudinally-spaced portions of said resistance element and whereby incident to arrestment of normal movements of said movable device with concurrent continued rotation of the leadscrew said portion of said wire engaging the leadscrew moves out of said groove and over said rib, thereby obviating damage to the potentiometer incident to arrestment of movement of said movable member.

18. A potentiometer according to claim 17, in which said contact-carrying member is electrically non-conductive and in which said resilient wire comprises a portion affixed to said contact-carrying member.

19. For a potentiometer of the type having a terminal and a rotatable leadscrew the rotation of which affects adjustment of resistance exhibited at terminals of the potentiometer, a movable device adapted to be moved by rotation of the leadscrew, said movable device comprising:

an electrically non-conductive member adapted to straddle the leadscrew and having portions adapted to be disposed at respective diametrically-opposite locations along the leadscrew, said member carrying electrically interconnected resilient brush means and having secured thereto a resilient bent wire having a first portion firmly secured to said member and a second portion connected to said first portion and free to be flexed, said wire having a third portion connected to said second portion and extending transversely across the leadscrew and adapted to engage in the groove of the thread of the leadscrew between successive convolutions of the rib of the thread whereby incident to rotation of such leadscrew said member is moved along the leadscrew until such movement is arrested and whereby incident to arrestment of said member during continuation of rotation of said leadscrew said third portion rides out of said groove and over said rib of the thread of the leadscrew to obviate damage.

20. A leadscrew-adjusted variable resistor comprising: first means, including an elongate housing having a body; an elongate resistance element mounted in said housing; a leadscrew rotatably supported by said housing and having a threaded portion exposed in said housing,

11

said leadscrew being arranged substantially parallel to said resistance element;
 a slider arranged for movement along said leadscrew in said housing, said first means comprising means preventing rotation of said slider around said leadscrew;
 a contact carried by said slider, said contact having a portion in electrical contact with said resistance element;
 a bent wire spring, insulated from said contact, carried 10 by said slider, said bent wire spring having a portion extending transversely across said leadscrew and normally engaged in the groove of the thread of the leadscrew whereby rotation of the leadscrew normally induces movement of the bent wire spring and 15 the slider along the leadscrew, a portion of said bent

12

wire spring yielding and snapping over the thread of the leadscrew as rotation of the leadscrew is continued to excess, and whereby said leadscrew is insulated from said contact; and means providing electrical connections to said contact and said resistance element.

UNITED STATES PATENT OFFICE
CERTIFICATE OF CORRECTION

Patent No. 3,124,779

March 10, 1964

Richard E. Caddock et al.

It is hereby certified that error appears in the above numbered patent requiring correction and that the said Letters Patent should read as corrected below.

Column 10, line 44, for "affects" read -- effects --.

Signed and sealed this 24th day of November 1964.
